UNITED STATES PATENT OFFICE.

CHARLES O'REARDON, OF OAKLAND, CALIFORNIA.

REPLACEABLE KNIFE AND JAW FOR PLIERS.

1,413,769.

Specification of Letters Patent. Patented Apr. 25, 1922.

Application filed March 8, 1920. Serial No. 364,080.

To all whom it may concern:

Be it known that I, CHARLES O'REARDON, a citizen of the United States, residing at Oakland, in the county of Alameda and 5 State of California, have invented certain new and useful Improvements in Replaceable Knives and Jaws for Pliers, of which the following is a specification.

In use, the cutting edge of pliers becomes 10 nicked and worn to such an extent that they become useless, necessitating a new pair.

The object of my invention therefore is to provide for the replacement of the worn parts, thus prolonging the usefulness of the 15 pliers. The present invention is an improvement on my invention shown in Patent No. 1,276,256, issued August 20, 1918.

Figure 1 is a side elevation of my improved pliers. Fig. 2 is a sectional view 20 taken on the line 2—2 of Fig. 1. Fig. 3 is a sectional view taken on the line 3—3 of Fig. 1. Fig. 4 is a perspective view of the cutting knife. Fig. 5 is a side elevation of a modified form of pliers. Fig. 6 is a sectional view taken on the line 6—6 of Fig. 5. Fig. 7 is a perspective view of one of the 25 plier jaws, embodying another modification of my invention with the knife and gripping jaw removed. Fig. 8 is a perspective view 30 of one of the replaceable gripping jaws.

Referring in detail to the drawings, 1 denotes a pair of pliers having gripping jaws 2 and 3, which are respectively provided with shanks 4 and 5 pivoted together in the 35 usual manner by a bolt 6. The jaws 2 and 3 of the pliers are of the usual construction but have their opposing surfaces formed at a portion adjacent the bolt 6 and remote from their extremities, with recesses 7 and 40 8 into which are fitted knives 10 and 9, respectively. The extremities of the opposing faces of the jaws may be formed, as shown in Figs. 5, 6 and 7, with recesses 17 and 18, respectively, which removably receive plates 45 16 and 15. These plates are corrugated or roughened on their opposite sides in order that they may be turned and reversed in the recesses as the corrugations wear from use. The plates 15 and 16 are held in position by 50 suitable screws 19 and 20 which pass therethrough and are each threadably engaged in an opening in the jaw, as clearly shown.

The knives 9 and 10 consist of plates having opposing cutting edges, each plate being provided with a recess or cutaway portion 55 thus providing the shoulders 14 and 13 on the plates respectively. These shoulders engage the inner edges of the recesses 8 and 9, respectively, while the plates are fitted in corresponding recesses on the sides of the 60 jaws and are removably held in position by the screws 12 and 11.

In Figs. 1 to 4, the knife is shown as being removable from the jaw, while in Figs. 5 and 6 the knife is of a permanent character. Fig. 7 shows one jaw of the pliers 65 which is modified to embody both features of this invention, namely, the removable knives and the removable gripping plates 70 15 and 16.

From the foregoing it is clear that the invention provides a simple and practical pliers having removable gripping plates and independently removable knives, the form shown in Fig. 7 embodying both of these 75 features, and possessing such construction and arrangement of parts as economically provides for a durable tool having independently and readily removable parts.

Having described my invention, I claim: 80

1. Pliers comprising a pair of pivotally connected gripping jaws having a recess in each of their opposing faces adjacent the free extremity thereof, flat gripping plates removably inserted in said recesses, other recesses formed in the opposing faces of said jaws at a point remote from their extremities and adjacent their point of pivot, plates removably inserted in said last-mentioned recesses and having cutting edges arranged 90 in opposed relation, and means for removably maintaining said last-mentioned plates in their respective recesses. 85

2. In combination with a pair of pliers having jaws, each provided with a recess in 95 the end of its gripping surface and each further provided with a recess in said surface inwardly of said first-mentioned recess, a side surface of each jaw also having a recess adjacent said inner recess, a gripping plate 100 for each jaw having a roughened surface, said plates being removably received in the recesses in the ends of the opposing surfaces of the jaws, and means for securing said

gripping plates in said recesses, a detachable knife for each jaw, each of said knives comprising a plate having a rabbet in one edge thereof, and a cutting edge formed on the opposite edge of said plate, one wall formed by the rabbet in said plate engaging in the recess in the side of the jaw and the other

wall of the rabbet engaging in the inner recess in the opposing face of the jaw, whereby the cutting edges are brought together 10 when the jaws are closed, and a fastening element extending through said knife plate.

In testimony whereof I affix my signature.

CHARLES O'REARDON.
